(57) **CLAIM**

The ornamental design for a vehicle, as shown and described.

DESCRIPTION

FIG. 1 is a front, left side, perspective view of the vehicle; FIG. 2 is a front, left side, perspective view thereof, wherein the convertible top and side windows are shown in a stowed position;

FIG. 3 is a rear, left side, perspective view thereof, wherein the convertible top and side windows are shown in a raised position;

FIG. 4 is a rear, left side, perspective view thereof, wherein the convertible top and side windows are shown in a stowed position;

FIG. 5 is a rear, top, right side, perspective view thereof, wherein the convertible top and side windows are shown in a stowed position;

FIG. 6 is a left side elevation view thereof, wherein the convertible top and side windows are shown in a raised position; FIG. 7 is a right side elevation view thereof, wherein the convertible top and side windows are shown in a raised position;

FIG. 8 is a left side elevation view thereof, wherein the convertible top and side windows are shown in a stowed position; FIG. 9 is a right side elevation view thereof, wherein the convertible top and side windows are shown in a stowed position;

FIG. 10 is a front elevation view thereof, wherein the convertible top and side windows are shown in a raised position; FIG. 11 is a rear elevation view thereof, wherein the convertible top and side windows are shown in a raised position;

FIG. 12 is a front elevation view thereof, wherein the convertible top and side windows are shown in a stowed position; FIG. 13 is a rear elevation view thereof, wherein the convertible top and side windows are shown in a stowed position;

FIG. 14 is a top plan view thereof, wherein the convertible top and side windows are shown in a raised position; and, FIG. 15 is a top plan view thereof, wherein the convertible top and side windows are shown in a stowed position.

The even broken lines shown in the drawings illustrate portions of the vehicle that forms no part of claimed design.

1 Claim, 13 Drawing Sheets
